United States Patent Office.

JOHN MORRISON HUNTER, OF MORRISTOWN, NEW JERSEY.

Letters Patent No. 78,970, dated June 16, 1868.

IMPROVED SOLES FOR BOOTS, &c.

The Schedule referred to in these Letters Patent and making part of the same.

TO ALL WHOM IT MAY CONCERN:

Be it known that I, JOHN MORRISON HUNTER, of Morristown, in the county of Morris, and State of New Jersey, have invented certain new and useful Improvements in Soles for Boots and Shoes; and I do hereby declare that the following is a full, clear, and exact description of the same, reference being had to the accompanying drawings, making a portion of this specification, in which—

Figure 1 is a vertical longitudinal section of a boot or shoe made according to my invention.

Figure 2 is a plan view of the same.

Figure 3 is an edge view of the same.

Similar letters of reference indicate corresponding parts in all the figures.

This invention consists in a novel construction of a sole for boots and shoes, whereby the same is not only rendered capable of resisting wear and abrasion, but is also made very light and elastic, and, furthermore, a non-conductor of heat to a much greater degree than is the case with the soles hitherto in use.

To enable others to understand the nature and construction of my invention, I will proceed to describe it with reference to the drawings.

A. represents a piece or plate of sheet metal, corresponding circumferentially with the outline of the forward portion of the sole to be formed or provided upon the boot or shoe, and having formed in one therewith the shank A*, this plate being preferably indented at its upper side, so that projections, a', are formed upon the lower surface of the same.

The plate A is designed to constitute the wearing-surface of the sole; and secured at the rear end of the shank A* thereof is a sheet-steel heel-shell, B, of the shape desired in the heel of the boot or shoe. The circumferential edges of the plate A and its shank A* are turned upward nearly or quite at right angles thereto, and are shaped or divided into spurs or lips, a, the office of which will presently herein appear. The corresponding upper edge of the shell B is, in like manner, formed with spurs or lips, b, designed to serve a similar purpose. Placed in the bottom of the shell B is a thickness, b*, of any suitable water-proof material, and at the rear end thereof is a semicircular piece, C, of steel. A thick layer, D, of cork is then placed in the shell, to constitute the filling thereof. Placed upon the sheet-metal plate A is a thickness, d, of water-proof material, upon which is laid a layer or thickness, e, of felt, or equivalent non-conductor of heat; and above this is a layer, f, of cork, the edges of which are surrounded by the leathern strip E. Placed upon the shank A* of the metallic plate A is a piece, B*, of leather, which, when desired, may be substituted by two lateral strips of the same material. Arranged circumferentially above the layer of cork in the shell B is a leathern strip, C*. The several parts being thus arranged, the spurs or lips a of the plate A, and the shank A*, together with those, b, of the heel-shell B, are turned over the contiguous edges of the strip E, piece B*, and strip C*, respectively, thus firmly securing the whole together to form the sole, which being done, the sole itself may be attached to the shoe by sewing or stitching the edges of the strips E C* and piece B* to the welt thereof.

It will be noticed that not only does the sheet metal provided upon the surface of the sole, in the manner described, preserve the same from wear and abrasion, but that the necessity of employing any material quantity of leather, such as the ordinary sole, is wholly dispensed with; while, from the nature and disposition of the materials employed, the sole, as thus made, is rendered much more impervious to water, and, at the same time, a less conductor of heat than such ordinary sole. Furthermore, it should be mentioned that, in case the corner at the rear end of the shell B, forming the heel, as hereinbefore described, should become worn through, the semicircular steel piece C will still resist any abrasive action exerted thereon, and thus preserve the heel in effective condition.

What I claim as my invention, and desire to secure by Letters Patent, is—

1. The sheet-metal outer sole A, A*, B, constructed with spurs or lips, a b, around its edge, for attachment to the boot or shoe, in the manner substantially as shown and described.
2. The combination of the sheet-metal sole A B, constructed as described, the cork tread and heel-filling f D, and leather strips E C*, with the welt of the boot or shoe, all arranged substantially as shown and specified.

J. MORRISON HUNTER.
